CONTINUOUSLY FED CENTRIFUGAL MACHINE

Alexander H. McPhee, Manhasset, N.Y., Charles A. Olcott, Hewitt, N.J., Thomas H. Reid, Brooklyn, N.Y., and Frederick Stindt, Cliffside Park, N.J., assignors to Hepworth Machine Company, Inc., Long Island City, N.Y., a corporation of New York

Application June 22, 1953, Serial No. 363,242

6 Claims. (Cl. 210—380)

This invention relates to centrifugal machines and more particularly to improvements in sugar centrifugal machines in which magma is fed continuously thereto.

It is an object of this invention to provide an improved continuously fed centrifugal machine which operates efficiently for both free-running and slow-running magmas.

Centrifugal machines of the continuous type have been proposed heretofore for the refining of sugar. In one such type, a perforated conical basket is provided and magma is continuously applied to the inside of the basket. The rotation of the basket results in centrifugal force which has the effect of causing the syrup or molasses to flow through the perforations in the side of the basket and causes the sugar to flow outward within the basket so that it can be discharged and kept separate from the liquid which has passed through the perforations. The holes in the basket are large enough to permit the escape of syrup but are small enough to retain the sugar in the basket.

The syrup escapes through the side of the basket into a conical skirt which is attached to and revolves with the basket. This skirt is not perforated so that the syrup flows into a first stationary housing where it is caught and discharged through a chute into a collecting canal for the syrup. A second stationary housing is provided with a chute for collecting the sugar. There is a space between the two stationary housings and this space is open to the atmosphere. It has been found that such a space is open to the atmosphere. It has been found that such a space is necessary because it is impossible to maintain the air pressure within the first housing always equal to that in the second housing. If there is a difference in pressure between these two housings and no space in between, there is an undesirable mixing of the sugar and syrup. Thus, if the air pressure in the second housing is higher than in the first one, sugar escapes from the second housing into the first and into the syrup, which is of course objectionable. Conversely, if the air pressure in the first housing is higher than that in the second housing, syrup flows from the first housing into the second and contaminates the dried sugar.

Machines of the type just described have been built and operated but their efficiency in separating sugar from syrup has been so low as to preclude their general use in drying sugar even though a machine of this type has been used successfully for separating solids other than sugar from a liquor. One of the principal reasons why such a machine has not been successful in drying sugar is that the characteristics of the sugar masses and magmas are subject to wide variation, particularly as to the facility with which the syrup leaves the sugar. It is obvious that the slope of the cone in such a machine must be such as to induce the molasses or syrup to flow through the holes and at the same time to permit the sugar to flow along the surface of the basket so that it escapes over the outside of the cone. If the slope of the cone is made very small, that is, if it is nearly cylindrical in shape, then the centrifugal force has a large

2

component to cause the escape of the syrup, but the component causing the sugar to flow is too small and thus the sugar tends to accumulate on the cone instead of flowing out over the edge. On the other hand, if the angle is too wide, then the masses and syrup flows out rapidly and may carry a large percentage of syrup along with the sugar to the housing which should receive only sugar.

It is apparent that if the magma is of a type which does not drain rapidly, the angle of the cone must be small so as to give plenty of opportunity for the syrup to escape and as the syrup is slow to escape then the mass remains relatively fluid and flows readily toward the outer diameter of the cone. Conversely, if the magma is free-draining, then the cone must have a wide angle to prevent the sugar from becoming so dry that it will not flow before it reaches the outer diameter of the cone. For this reason, in such a machine it is desirable that the relation between the force tending to move the material along the surface of the cone and the force tending to bring the syrup through the cone should be subject to adjustment for each grade of sugar being dried. It is obvious that, as a practical matter, it is impossible to construct a cone which is varied as to its angle without going into so many complications as to make the machine extremely expensive to construct and to maintain.

It is, accordingly, another object of this invention to produce substantially the results which would be obtained from a cone of varied angle and at the same time to avoid expensive and troublesome complications in construction.

The present invention is based on the discovery that by positioning blower vanes of suitable design at the outside of the rotating basket in the space between the latter and the conical skirt surrounding it, a vacuum can be created in this space which increases the force tending to cause the syrup to flow through the holes in the basket. This force also can actually increase the rapidity of the drying of the sugar and it tends to hold the sugar against the inside of the cone. In other words, it has the same effect as reducing the included angle of the cone. Thus, in accordance with the invention, there is provided a centrifugal of the same general type as that described above having a cone of a relatively wide angle but, because it is equipped with the above-mentioned vanes, operates substantially like a cone of a smaller angle.

Moreover, in accordance with the invention, the degree of vacuum in this space between the basket and the skirt is varied by varying the opening in the chute through which the syrup passes after it has been flung through the apertures in the basket. Thus, if this opening in the chute is nearly cut off by a damper, the vacuum caused by the vanes will be greatly reduced and the cone operates substantially in the manner of a wide angle cone. However, if the damper is turned with the flow through the chute, then the vacuum acts to accelerate drainage and to hold the sugar against the inside of the cone and then the latter behaves as if it were a cone with a smaller angle. Movement of the damper to intermediate positions between fully open and fully closed ones operates to cause the same effect as progressively changing the included angle of the cone.

The invention will be more readily understood by referring to the following description taken in connection with the accompanying drawings forming a part thereof, in which:

Fig. 1 is an elevation view, with portions in cross-section, of a centrifugal machine of the continuous type in accordance with the invention together with equipment related thereto; and

Fig. 2 is a cross-section view of one of the housings and the rotating member of the machine of Fig. 1 taken

in a plane through line 2-2 in Fig. 1 and looking in the direction of the arrows.

Referring more specifically to the drawings, Fig. 1 shows, by way of example for purposes of illustration, a sugar centrifugal installation 10 embodying a centrifugal machine 11 of the continuous type in accordance with the invention and certain related pieces of equipment which will be described below and which are associated with it in its operation.

The centrifugal machine 11 comprises a first stationary 10 housing 12, a second stationary housing 13 separated from it, and a member 14 adapted to rotate within and between these housings. The rotating member 14 includes a conical basket 15, the sides of which (or of a lining thereof) are provided with a multiplicity of apertures 16 through which syrup flows during the centrifuging process into the housing 12, and a conical skirt 17 attached to and adapted to rotate with the basket 15. The basket is attached to and rotated by a shaft 18 supported within suitable bearings, such as the member 19, 20 and driven by suitable means such as the motor 20.

Massecuite is applied to the interior of the basket 15 from the source 21, which may be any suitable mixing pan or tank, through the pipe 22. Under the action of centrifugal force caused by the rotation of the basket 15, the syrup is forced through the apertures 16 into the space between the basket 15 and the skirt 17 and thence into the first stationary housing 12 which is connected at its lower end to a chute 23 which empties into a canal or container 24. The sugar grains left after the syrup has been driven off flow to the right and finally escape from the conical basket 15 and are caught by the second stationary housing 13 which empties through chute 25 into a conveyor 26 which carries the sugar away.

There is a space between the two housings 12 and 13 and this space is open to the atmosphere. As pointed out above, this space is necessary because it is impossible to maintain the air pressures within the housings 12 and 13 always equal and if there is a difference in pressure between these two housings and no space in between, the syrup and sugar will become mixed.

Since the grade of sugar being processed frequently varies from batch to batch, it is desirable that the relation between the force tending to move the material along the surface of the conical basket 15 and the force tending to bring the syrup through the apertures 16 should be subject to adjustment for each grade of sugar being dried. Before the present invention, it would be necessary to vary the angle of the conical basket 15 in order to attain this desirable result. As already pointed out, such an arrangement would be so expensive as to be completely impractical in most situations.

This result is, however, simply and relatively inexpensively attained in accordance with the present invention by creating a partial vacuum, the pressure of which can be varied, in the space between the conical skirt 17 and the conical basket 15. This is accomplished by providing blower vanes 27 attached to the rotating member 14 (either to the basket 15 or the skirt 17) and suitably shaped to produce a partial vacuum in the region between the basket and the skirt. If desired, the vanes may be flat or any other convenient shape. In the drawings, the vanes are shown by way of example attached to the skirt 17. This increases the force tending to cause the syrup to flow through the holes 16 in the basket 15. This force also increases the rapidity of the sugar drying process and tends to hold the sugar against the inside of the conical basket 15, thus having the same effect as reducing the included angle of the cone. This means that the slope of the cone 16 can be effectively changed (as far as operation is concerned) without actually varying the slope itself.

Control of the effective change in slope is obtained, in accordance with this invention, by varying the degree of

vacuum in the space between the skirt 17 and the basket 15. One satisfactory way of doing this is to place a damper 28 in the chute 23. When this damper is positioned to cut off the opening in the chute 23, the vacuum caused by the vanes 27 will not be very high and the basket 15 operates substantially as a wide angle cone. When the damper 28 is in the fully open position (upright in Fig. 1), the resulting vacuum acts to accelerate the drainage and to hold the sugar grains against the inside of the basket, thus acting as if it were a smaller angle cone. Intermediate positions of the damper 28 (such as that shown in Fig. 1) operate to produce substantially the same effect as cones between wide angle and small angle types. Obviously, the equivalent of a series of cones of progressively different slopes is produced by the arrangement just described. The pressure between the skirt 17 and the basket 15 can be adjusted to suit the drainage characteristics of the magma being employed.

Obviously, the invention is not limited to the specific structure described above as various changes can be made therein without departing from the spirit or letter of the invention, as indicated in the claims.

What is claimed is:

25 1. A sugar-drying centrifugal machine comprising a rotatable basket having a multiplicity of apertures therein, means for continually feeding magma to the interior of said basket, means including a circular skirt surrounding and adapted to rotate with said basket for directing away from the basket liquid from said magma thrown off during the sugar drying process, means for producing a pressure lower than atmospheric pressure in the region between said basket and said skirt, and means separate from said last-mentioned means for varying said pressure.

30 2. A sugar-drying centrifugal machine comprising a rotatable basket having a multiplicity of apertures therein, means for continually feeding magma to the interior of said basket, means including a circular skirt surrounding and adapted to rotate with said basket for directing away from the basket liquid from said magma thrown off during the sugar drying process, means for producing a pressure lower than atmospheric pressure in the region between said basket and said skirt, said last-mentioned means including a plurality of vanes positioned to rotate with said basket, and means separate from said pressure producing means for varying said pressure.

35 3. A sugar-drying centrifugal machine comprising a rotatable basket having a multiplicity of apertures therein, means for continually feeding magma to the interior of said basket, means including a circular skirt surrounding and adapted to rotate with said basket for directing away from the basket liquid from said magma thrown off during the sugar drying process, said last-mentioned means also including a chute, and damper means in said chute for varying the flow therethrough.

40 4. A sugar-drying centrifugal machine comprising a rotatable basket having a multiplicity of apertures therein, means for continually feeding magma to the interior of said basket, means including a circular skirt surrounding and adapted to rotate with said basket for directing away from the basket liquid from said magma thrown off during the sugar drying process, said last-mentioned means also including a chute, means for producing a pressure lower than atmospheric pressure in the region between said basket and said skirt, and damper means in said chute for varying said pressure.

45 5. A sugar-drying centrifugal machine comprising a rotatable basket having a multiplicity of apertures therein, means for continually feeding magma to the interior of said basket, means including a circular skirt surrounding and adapted to rotate with said basket for directing away from the basket liquid from said magma thrown off during the sugar drying process, said last-mentioned means also including a chute, means including a plurality of vanes attached to the periphery of said

basket and adapted to rotate therewith for producing a pressure lower than atmospheric pressure in the region between said basket and said skirt, and means in said chute for varying said pressure.

6. A sugar-drying centrifugal machine comprising a 5 rotatable basket having a multiplicity of apertures therein, means for continually feeding magma to the interior of said basket, means including a circular skirt surrounding and adapted to rotate with said basket for directing away from the basket liquid from said magma 10 thrown off during the sugar drying process, said last-mentioned means also including a chute, means including a plurality of vanes positioned to rotate with said basket

for producing a pressure lower than atmospheric pressure in the region between said basket and said skirt, and damper means in said chute for varying said pressure.
